VALVE FOR THE CONTROL OF HYDRAULIC PRESSES

Merril R. Lieb, Allentown, and Walter W. Wassum, Alburtis, Pa.

Application June 22, 1938, Serial No. 215,244

1 Claim. (Cl. 251—20)

This invention relates to valves for controlling the fluid pressure employed for the operation of hydraulic presses and of the character set forth in our copending application Serial No. 176,322 and filed November 24, 1937, now Patent No. 2,152,551, granted March 28, 1939, and has for the primary object the provision of means for increasing the efficiency of the device by balancing the pressure against the pressure control valve elements of the valve either when closed or opened so as to require less power for the operation or movement of said valve elements to their different positions.

Another object of this invention is the provision of means which improves the valve elements to prevent leakage of pressure either when closed or opened.

With these and other objects in view, the invention consists in certain novel features of construction, combination and arrangement of parts to be hereinafter more fully described and claimed.

For a complete understanding of our invention, reference is to be had to the following description and accompanying drawings, in which

Figure 1 is a vertical sectional view illustrating a valve constructed in accordance with the present invention.

Figure 2 is a top plan view illustrating the same.

Figure 3 is a sectional view taken on the line 3—3 of Figure 1 looking in the direction indicated by the arrows.

Figure 4 is a sectional view taken on the line 4—4 of Figure 1 looking in the direction indicated by the arrows.

Figure 5 is an end view illustrating one end of the body portion of one of the valve elements.

Figure 6 is a sectional view taken on the line 6—6 of Figure 5.

Figure 7 is an end view illustrating a valve head detachably secured on the body portion of the valve element.

Figure 8 is a sectional view taken on the line 8—8 of Figure 7.

Figure 9 is a diagrammatical view illustrating passages in the valve and the connection of said passages to opposite ends of a cylinder forming a part of a hydraulic press (not shown).

Referring in detail to the drawings, the numeral 10 indicates a power cylinder forming a part of a hydraulic press (not shown) while the piston of said cylinder is indicated by the character 11 and is adapted for reciprocation in the cylinder under fluid pressure. The ends of the

cylinder have connected thereto pipes 12 and 13 for admitting and exhausting fluid pressure to said cylinder 10 for the reciprocation of the piston. The pipes 12 and 13 are connected to a valve 14 forming the subject matter of the present invention.

The valve 14 includes a body 15 in which are arranged pairs of vertically disposed chambers 16 for the reception of pairs of valve elements 17 and 18. The valve elements 17 are for controlling fluid pressure from a source to the ends of the cylinder 10 and the valve elements 18 are for controlling fluid pressure from the cylinder 10 back to the supply or to the atmosphere. The valve elements 17 will be hereinafter known as 15 pressure control valves while the valve elements 18 will be known as return valves. The valve elements 17 are diagonally arranged to each other also the valve elements 18 are diagonally arranged to each other and are adapted for reciprocation in their respective chambers 16 which open outwardly through the top wall of the body 15 and have threaded therein packing gland sleeves 19 engageable with packing 20 to force said packing against the valve elements to prevent leakage. Mounted in the chambers 16 are valve seats 21. Each of the valve elements has its inner end shaped or designed to form a substantially U-shaped flange 22 to receive a grooved head 23 of a seat engaging element 24. The element 24 has a beveled face 25 to engage with a seat 21 and also includes a skirt 26 slidably within the walls of the sleeve. The skirt below the face 25 has a series of ports 27 which will permit a flow of fluid through the skirt when the face 25 is disengaged from the seat.

The seat engaging elements 24 may be readily detached from the valve elements 17 and 18 when the latter are removed from the chambers 16. However, said seat engaging elements are prevented from becoming accidentally disconnected from said valve elements 17 and 18 when the latter are mounted for operation in the chambers 16 due to the fact that the skirts 26 always remain in contact with the seats 21 or the walls 40 thereof during all positions of the valve elements.

The valve elements 18 include elongated cylindrical portions for the packing 20 to engage and reduce screw threaded portions 28 arranged exteriorly of the body for connection with an operating means which will be hereinafter more fully described. The valve elements 17 include cylindrical portions 30 and 31 of different external diameters. The cylindrical portions 31 of the valve elements 17 provide piston-like portions 50

thereto and are engaged by packings 32 arranged in the chambers 16 of the valve elements 17 between the packing gland and seat 33 provided therefor. The packings 32 also engage with the 5 cylindrical portions 30 of the valve elements 17. Between the packing gland sleeves 19 of the chambers 16 which receive the valve elements 17 and the cylindrical portions 31 are formed pressure chambers 34. The pressure chambers 10 10 15 20 25 30 35 34 below the cylindrical portions 31 are open to the atmosphere by vents 35 provided in the body 15 of the valve. The valve elements 17 also include reduced screw threaded portions 28 to permit said valve elements 17 to be connected 15 with the operating means.

The body 15 of the valve has fluid chambers 36 which are located in the chambers 16 of the body and in which the valve seats 21 are located. The fluid chambers 36 extend above and below 20 25 30 35 the valve seats. The lower portions of the fluid chambers 36 of the valve elements 17 are connected to the pressure chambers 34 by bypass pipes 37.

The purpose of the bypass pipes 37 is to permit 25 30 35 equal fluid pressure to be had between the lower portions of the fluid chambers and the pressure chambers 34.

Formed in the body 15 of the valve is an intake passage 38 connecting with the upper portion 30 35 40 45 50 55 of the fluid chambers 36 of the valve elements 17 and with a fluid pressure source (not shown). The body of the valve is also provided with an exhaust passage 39 connecting with the lower end of the fluid chambers 36 and opening outwardly of the valve body to the atmosphere or may be suitably connected with the fluid pressure source for the return of fluid thereto. The valve body is provided with ports or passages 40 connecting with the lower portions of the fluid chambers 36 of the pressure control valve elements 17 and one of the ports 40 is connected to one end of the cylinder 10 by a pipe 41 while the other port 40 is connected to the other end of the cylinder 10 by a pipe 41'. Passages 42 connect the lower portions of the fluid chambers 36 of the pressure control valve elements 17 to the upper portions of the fluid chambers of the return valve elements 18, as clearly shown in Figure 9. Further, it is to be noted that the passages 42 connect the fluid chambers 36 in such a way that fluid may flow between the fluid chambers of the valve elements 17 and 18 that are arranged in opposite pairs.

The operating means indicated in entirety by 55 the character 43 forms the subject matter of a copending application filed on even date with the filing of this present application and will be briefly set forth herein for the purpose of giving a clear understanding as to the operation of the 60 present invention. A saddle 44 is mounted on the body of the valve and slidably supports blocks 45 secured on the portions 28 of the valve elements 17 and 18 by nuts 46. The blocks 45 are provided with notches 47 to receive teeth or ribs 48 on shafts 49 journaled in the saddle 44. Arms 50 are secured on the shafts 49 and are pivotally connected to an operating lever 51 by linkage 52. Pivotal movement of the operating lever 51 in opposite directions brings about rotation of the 65 70 75 shafts 49 in opposite directions. The connection of the shafts 49 with the valve elements 17 and 18 is such that the valve elements will be simultaneously reciprocated and the pair of valve elements 17 reciprocated in opposite direction to each other and the valve elements 18 reciprocated in

opposite direction to each other. Thus it will be seen that when one of the valve elements 17 is in a seated position the other valve element 17 will be in an unseated position which also applies to the valve elements 18. A movement of 5 the operating lever 51 in one direction unseats one of the valve elements 17 and one of the valve elements 18 which permits a flow of fluid pressure from the source (not shown) to one end of the cylinder while the opposite end of the cylinder 10 is exhausting. The flow of the fluid is indicated by the arrows in Figure 9 entering the passage 38 to the upper portion of the fluid chambers 36 and as one of the valve elements 17 is unseated fluid flows past the seat into the lower portion 15 of the fluid chamber 36 of said unseated valve element 17 and through the pipe 41 to one end of the cylinder 10, thereby forcing the piston 11 to the left in Figure 9. The fluid to the left of the piston 11 leaves the cylinder 10 by way of the 20 pipe 41', enters the lower portion of the fluid chamber 36 of the seated valve element 17 through one of the passages 42 to the upper portion 25 of the fluid chamber 36 of the unseated valve element 18 and downwardly past the seat 21 25 thereof to the exhaust passage 39 whence the fluid may exhaust to the atmosphere or return to the fluid pressure supply through the medium (not shown) if connected to the exhaust passage 39. The flow of the fluid is reverse to that just 30 described and indicated by the arrows in Figure 9 when the operating lever 51 is moved in an opposite direction to bring about movement of the piston 11 in the cylinder 10 to the right in Figure 9.

Due to the arrangement of the passages and ports as described in detail and their connection with the fluid pressure source the upper portions 40 45 50 55 60 65 70 75 80 85 90 95 of the fluid chambers 36 of the pressure control valve elements 17 are always in direct communication with the fluid pressure source so that the pressure of the fluid will act in an upward direction on the lower ends of the valve elements 17 and also on the seat engaging elements thereof in a downward direction which brings about a balanced pressure on the valve elements 17, consequently permitting the valve elements 17 to be moved off of their seats with a minimum amount of force applied through the actuation of the operating means 43. Due to the connection between the seat engaging elements and the bodies of the valve elements 17 spaces are provided therebetween which permits the fluid pressure to act in opposite directions on the valve elements so that a minimum amount of force is only necessary to unseat the valve elements 17. When the valve elements 17 are unseated the fluid pressure then becomes equal throughout the entire areas of the fluid chambers 36 of the valve elements 17. The fluid pressure then may enter the chambers 34 by way of the bypass pipes 37. The fluid pressure is then acting on the valve elements 17 in opposite directions bringing about floating of the valve elements 17 while unseated, consequently requiring only a minimum amount of force to move the valve elements 17 from unseated position to seated position. The fluid pressure in the chambers 34 acts upon the cylindrical portions 31 of the valve elements 17 in a downward direction while the fluid pressure in the upper portion of the fluid chambers acts on the valve elements 17 in an upward direction bringing about floating of the valve elements 17 when unseated. Thus it will be seen that it will require very little force in the movement of the 75

valve elements 17 in either direction and as the valve elements 18 are only subjected to low fluid pressure, the operation of the valve can be brought about with a minimum amount or expenditure of manual effort or fluid pressure if the operating lever 51 is so actuated.

10 It is believed that the foregoing description, when taken in connection with the drawings will fully set forth the construction and advantages of this invention to those skilled in the art to which such a device relates, so that further detailed description will not be required.

Having thus described the invention what we claim is:

- 15 In a valve, a body provided with an elongated bore having different size dimensions to form a shoulder within said bore, one end of said bore opening outwardly through a face of the body and the other end being provided with a fluid pressure exhaust, a stuffing box removably and adjustably mounted in the first-mentioned end of the bore, a seat in the bore and spaced from said shoulder and the fluid pressure exhaust, packing located in the bore and bearing against the shoulder and the stuffing box and having contact with the walls of the bore from the shoulder to the stuffing box, a slidably valve element in said bore and having valve opening and closing
  - 20
  - 25

positions and including a stem slidable through the stuffing box and a piston and a plunger integrally connected and having slidable fit with the packing, said packing and seat defining therebetween a fluid pressure chamber in the bore with a portion of the plunger therein, means for admitting constant fluid pressure to said chamber, said packing, piston and stuffing box coacting to form a second fluid pressure chamber in the bore, operating means located exteriorly of the body and connected to the stem for sliding the valve element in opposite directions to engage and disengage the plunger with the seat, said piston having an area exposed to the second-mentioned fluid pressure chamber equal to the area of the plunger exposed to the first fluid pressure chamber when said plunger is disengaged from the seat, and a bypass pipe connecting the first-named fluid pressure chamber to the fluid pressure exhaust for admitting fluid pressure from the first-mentioned fluid pressure chamber to the second-mentioned fluid pressure chamber when the plunger is disengaged from the seat for balancing the valve element when in valve opening position.

MERRIL R. LIEB.
